UNITED STATES PATENT OFFICE.

HITCHCOCK Z. ANGEVINE, OF LOS ANGELES, CALIFORNIA, ASSIGNOR OF ONE-THIRD TO CHARLES EDWARD JONES, OF LANCASTER, CALIFORNIA.

BOOT AND SHOE.

No. 895,140.

Specification of Letters Patent.

Patented Aug. 4, 1908.

Application filed September 26, 1906. Serial No. 336,355.

To all whom it may concern:

Be it known that I, HITCHCOCK ZENTS ANGEVINE, of the city of Los Angeles, in the county of Los Angeles, in the State of California, have invented certain new and useful Improvements in Boots and Shoes, of which the following is a full, clear, and exact specification, reference being had to the annexed drawings and to the letters and figures 10 marked thereon.

My said invention which relates to certain new and useful improvements in boots and shoes, has for its object to enable the bottom or lowest part of the heels of boots and shoes 15 to be easily removed when worn, and to be easily replaced by a new or unworn bottom part when required.

My invention is such that the removable and replaceable bottom or wearing part of 20 the heels of boots or shoes is easily removed and replaced without necessitating resort to the services of a boot or shoe maker or repairer.

My invention consists in constructing the 25 heel portion of a boot or shoe with a hollow or receptacle of sufficient depth or height therein, wherein the operative parts of my device are contained.

The operative parts of my device consist 30 of a plate fastened to its edges by nails, or brads, or spikes, driven into the wood or leather or other material, of which the heel of a boot or shoe is constructed. This plate is a covering plate for inclosing the bottom 35 of a recess in the heel of a boot or shoe wherein two adjustable plates having holes or indentations for engaging with, and firmly holding or retaining in the boot or shoe certain studs and the parts connected therewith, are contained. These studs project 40 upwards from the lower halves of a series of snappers, which engage with a corresponding series of the upper halves of snappers, or equivalent recesses in the plate wherein the 45 upper parts of these snappers are contained. The lower halves of the snappers are contained in, or fastened to, the removable plate of metal, or other material, which constitutes the treading surface of the heel, and 50 when the two halves of the several snappers are placed together so as to engage with each other, then the movable lower portion of the heel is fastened to the upper part of the heel and the studs provided with a head project 55 upwards from the center of the lower half of

each snapper, passing through the upper part of the snapper, and through corresponding holes in the plates fastened to the inside of the hollow of the heel and movable plates operated by a right and left hand screw, 60 which on being rotated in either a right or left hand direction cause the holes or catches in the two movable plates to engage with the studs, and thereby to retain the bottom or tread plate firmly in place.

The entire device constituting my invention operates as is next herein set forth, with reference to the annexed drawings of which

Figure 1, is a longitudinal section of the heel of a boot or shoe constructed in accordance with my present invention. Fig. 2, is an enlarged section of the lower part of the heel showing the arrangement and construction of the parts more distinctly than in Fig. 1. Fig. 3, is a detailed plan of the two movable plates and the right and left hand screws for operating them. Fig. 4, is a plan of the plate which covers over the movable plates shown at Fig. 3, and the right and left hand screws therein. Fig. 5, is a plan of the 80 plate containing the lower halves of the snappers. Fig. 6, is a plan of the plate containing the upper halves of the snappers. Fig. 7, is a plan of a vulcanized india rubber pad fastened to the lower hollow part of the heels 85 of a boot or shoe, by cement and nails, or otherwise fastened thereto.

As shown by Fig. 1, my new or improved heel is or may be constructed of a series of lifts *a*, *b*, *c*, *d*, *e*, *f*, and *g*, respectively, as 90 shown at Fig. 1. A hollow or receptacle marked *B*, extends upwards into the heel as shown in Fig. 1, of the drawings. Along the center of the heel as shown at Fig. 1, there extends a sufficient opening to permit of the 95 right and left hand screw shaft *C*, to pass horizontally therethrough.

The right and left hand screws upon the shaft *C*, are shown by the inclinations in opposite directions of the screw threads *D*, *D'*, 100 respectively, engaging with correspondingly tapped portions of the two movable plates *E*, and *E'*. The outer end of the shaft *C*, is made square as shown at Figs. 1, and 3, for the purpose of admitting of the temporarily 105 placing thereon, a handle or key for rotating the right and left hand screws *D*, *D'*, for moving the right and left hand movable plates *E*, and *E'*, nearer to or further from each other as required. In the movable 110

plates E, and E', there are holes F, and F', respectively, as may be more particularly seen in plan, Fig. 3.

The two plates E, and E', are carried upon the plate H, H, which is fastened by brads or nails to the material constituting the heel of the boot, as shown more especially in Figs. 1, 4, and 6. The plate H, H, constitutes an efficient flat sliding surface for the plates D, and D', to be moved backwards and forwards upon. Another plate I, as shown in Figs. 1, and 2, and in Fig. 5, is situate beneath the other parts of the heel which are hereinbefore described, and a lining of vulcanized india rubber J, or of analogous material is placed between the plate I, and the plate H, H. This pad of india rubber or analogous material is shown at Fig. 7, and this pad is fastened to the body of the heel by nails or brads being driven through it and into the material of the said heel, as shown at Figs. 1, and 7. The plate I, is the plate which carries the larger, that is to say, the upper half of each of the several snappers K, as shown at Figs. 1, 2, and 6, while the smaller halves K', of the snappers are fastened to the bottom plate G, and these smaller halves K', of the snappers K, and studs with heads marked h, project upwards through the holes in the upper halves of the snappers K, through holes in the plate H, and into and through the holes or recesses F, and F', in the two sliding plates E, and E'.

When the lower plate G, with its smaller and lower halves of the snappers K, fastened thereto, which smaller halves of said snappers have each a stud head h, projecting upwards from it, is to be inserted so as to be held securely in my new or improved heel, then the screw shaft C, is so turned that the holes or recesses F, and F', in the plates E, and E', are situated centrally over the snappers so that

the heads and studs h, of the snappers may pass up through and into the upper halves of the snappers K, fastened as already explained 45 into the plate I, without interference by the holes or recesses F, and F', in the two plates E, and E', and when the lower plate G, has been thus placed so as to be in touch all round with the pad J, then the screw shaft C, with its right 50 and left hand screws D, and D', is turned in the direction to move the two plates E, and E', so that the holes or recesses F, and F', therein, are under the heads of the studs h, and thereby hold the bottom plate G, in operative 55 position.

I claim as my invention.

In heels for boots and shoes, the device comprising the combination of a series of snappers, the smaller part of each of which 60 carries a vertical projecting stud and head which passes into and through an opening in the larger part of the snappers, the sliding plates operated by right and left hand screws and having openings for engaging with the 65 studs and heads of the smaller halves of the snappers, the plate upon which the sliding plates are supported and moved, the plate carrying the larger part of the snappers, the plate carrying the smaller part of the snappers with studs and heads, the elastic pad, all contained in and fastened to the heel of a 70 boot or shoe and operating together in the manner and for the purposes substantially as hereinbefore described.

In testimony whereof, I, the said HITCHCOCK ZENUS ANGEVINE, have hereunto set my hand and seal in the presence of two subscribing witnesses.

HITCHCOCK Z. ANGEVINE. [L. s.]
